(57) **CLAIM**

We claim the ornamental design for a gaming machine archway with overhead display screen, as shown and described.

DESCRIPTION

The present application is related to U.S. patent application Ser. No. 29/698,535, filed Jul. 17, 2019, entitled “Gaming Machine Archway With Overhead Display Screen,” and U.S. patent application Ser. No. 29/698,539, filed Jul. 17, 2019, entitled “Gaming Machine Archway With Overhead Display Screen.”

FIG. 1 is a perspective view of a first embodiment of a gaming machine archway with overhead display screen showing the new design;

FIG. 2 is a lower perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a left-facing cross-sectional view thereof taken along line “9-9” of FIG. 3, the right-facing sectional view being a mirror image thereof;

FIG. 10 is a perspective view of a second embodiment of a gaming machine archway with overhead display screen showing the new design;

FIG. 11 is a lower perspective view thereof;

FIG. 12 is a front view thereof;

FIG. 13 is a rear view thereof;

FIG. 14 is a left side view thereof;

FIG. 15 is a right side view thereof;

FIG. 16 is a top view thereof;

(Continued)

FIG. 17 is a bottom view thereof; and,
 FIG. 18 is a left-facing cross-sectional view thereof taken along line “18-18” of FIG. 12, the right-facing sectional view being a mirror image thereof.
 The broken line showing of portions of the gaming machine archway with overhead display screen forms no part of the claim.
 The claimed design is shown with a symbolic break in its length. The appearance of any portion of the article between the break lines forms no part of the claimed design.
